DESIGN FOR A CABINET OR SIMILAR ARTICLE

Frank D. Kissel and Paul P. Runnels, Indianapolis, Ind.

Application February 26, 1934, Serial No. 50,887

Term of patent 14 years

To all whom it may concern:

Be it known that, FRANK D. KISSEL and PAUL P. RUNNELS, citizens of the United States, residing at Indianapolis, in the county of Marion and State of Indiana, have invented a new, original, and ornamental Design for Cabinets or Similar Articles, of which the following is a specification.

Reference is made to the accompanying drawing, in which

Fig. 1 is a front perspective view of a cabinet, showing our new design; and

Fig. 2, a rear elevation.

We claim:

The ornamental design for a cabinet or similar article, substantially as shown.

In testimony whereof we affix our signatures.

FRANK D. KISSEL.
PAUL P. RUNNELS.
